UNITED STATES PATENT OFFICE.

ROLLIN H. WHITE, OF CLEVELAND, OHIO, ASSIGNOR TO THE WHITE SEWING MACHINE COMPANY, OF CLEVELAND, OHIO, A CORPORATION OF OHIO.

STACK CONSTRUCTION FOR STEAM-CARRIAGES.

SPECIFICATION forming part of Letters Patent No. 740,208, dated September 29, 1903.

Application filed November 17, 1902. Serial No. 131,639. (No model.)

To all whom it may concern:

Be it known that I, ROLLIN H. WHITE, a citizen of the United States, residing at Cleveland, in the county of Cuyahoga and State 5 of Ohio, have invented a certain new and useful Improvement in Stack Construction for Steam-Carriages, of which the following is a full, clear, and exact description, reference being had to the accompanying drawings.

10 The object of the present invention is to provide suitable stack construction for steam-carriages whereby to produce a sufficient draft to promote combustion and whereby the products of combustion and waste heat will 15 be discharged in such manner as not to annoy passengers.

The invention may be summarized as consisting of the construction and combinations of parts hereinafter described, and pointed 20 out definitely in the claims.

In the drawings, Figure 1 is a side view of my invention and so much of a steam-carriage as is necessary for the understanding of the invention. Fig. 2 is a plan view thereof, partly in section; and Fig. 3 is a front end view of the draft apparatus on one side of the vehicle.

In steam-carriages the generator is heated usually by an oil-burner, and the generator 30 is covered by a hood or casing from which the products of combustion are discharged through suitable flues, usually called the "stacks." It is desirable that the stacks discharge the products of combustion at such 35 points that the passengers will not be annoyed thereby, and it is also necessary that there shall be a sufficient draft through the stack to promote proper combustion at the burner. This problem has heretofore been 40 most satisfactorily solved by turning the stack downward, so that it discharges beneath the carriage, and by discharging the exhaust-steam into this downturned stack, so as to create therein a forced downdraft. It 45 is not practical, however, to use a downturned stack in a steam-carriage which condenses the exhaust-steam, because there is no way of creating the necessary downdraft. By the construction hereinafter described, 50 and shown in the drawings, the desired re-

sults are satisfactorily attained without using the exhaust-steam to create a draft, and it is therefore particularly useful in a steam-carriage having a condenser.

Referring to the parts by letters, A represents the carriage-body, and D the hood or casing which covers the generator B. The burner, which is not shown, is of course located below the generator, and the waste heat and products of combustion rise past said 55 generator into the upper end of said hood. The upper end of the hood D is closed, save for two laterally-extended draft-tubes d d, which extend out through the sides of the body, where they discharge into the horizontal longitudinally-extended stacks E between the ends of said stacks. The stacks are open 60 at both ends and are suitably close to the body A. As shown, they are supported by their connection with the outer ends of the 65 pipes d d.

The forward movement of the carriage creates an air-current rearward through these longitudinal horizontal stacks. Under certain conditions which arise in practice these 70 air-currents entering the front ends of these stacks might produce a back pressure in the draft-tubes d, and thereby diminish the normal draft. To prevent this, when the carriage is moving forward I place in each of the 75 horizontal stacks a deflector K, which is located just in front of the draft-tube d and projects from the inner side of the horizontal stack approximately two-thirds of the distance across the same. The opening which 80 remains between the outer edges of the deflector and the outer wall of the horizontal stack should be large enough to produce the necessary draft; but the deflector acts to prevent the air-current entering the front end of 85 the stack from flowing into the draft-tubes d. If a steam-carriage had never to be moved rearward, this deflector might be permanently fixed; but since it is sometimes necessary to drive the carriage backward it is desirable to 90 employ two of these deflectors, located one just in front of and one just behind the draft, the former for use as a deflector when the carriage is moving forward and the latter for a like use when the carriage is moving rear- 95 100

ward. The deflector which is not serving the purpose stated is for the time being useless. In the construction shown, therefore, there is provided in each of the horizontal stacks two of these deflectors, which are pivoted on vertical axes near the inner wall of the stack, wherefore they are capable of severally swinging into operative position or of lying substantially flat against the inner wall of the stack. These two swinging deflectors are connected together by a wire N of such length that when one of the deflectors extends as far as may be across the stack the other one lies flat against the side thereof.

In the operation of the carriage when an air-current is flowing rearward through the stacks, whether such current is due to the forward movement of the carriage or to the wind when the carriage is standing, the air-current entering the front end of each stack will by its action upon these deflectors cause them to assume the position shown in the drawings—that is to say, the front deflector will extend across the stack, while the rear deflector will lie flat against the side. If the direction of the air-current in the stacks is reversed, so that it enters the rear end of said stacks, said current will automatically reverse the position of these deflectors, and thus the deflectors will under all conditions which arise automatically take those positions which are necessary for the proper performance of the described functions.

In automobiles it is a practical necessity that mud-guards be provided. The mud-guards for the rear wheels are indicated by G in the drawings, and, as shown, they extend down part way in front of the rear wheels, and horizontally backward over the wheels to or beyond the rear end of the carriage-body. These mud-guards are fastened rigidly to the carriage-body. As shown, the front ends are so fastened by the bracket-arms g , while the rear parts are nailed or otherwise fastened to the under side of the overhanging tonneau-seats. The rear ends of the horizontal stacks are extended through and under these mud-guards, and therefore the products of combustion and waste heat as the carriage is moving forward will be dis-

charged beneath these mud-guards, which then serve the additional purpose of guiding or deflecting these products of combustion, &c., so that they will certainly be delivered from beneath said mud-guards at the extreme rear end of the carriage.

Having described my invention, I claim—

1. In a steam-carriage in combination with a mud-guard, a horizontal longitudinally-extended stack open at both ends and located outside the carriage-body, one end of said stack extending through one of the mud-guards, and a draft-tube connected with said stack, substantially as described.

2. In a steam-carriage in combination with a mud-guard, a horizontal longitudinally-extended stack open at both ends and located outside the carriage-body, one end of said stack extending through one of the mud-guards, a draft-tube connected with said stack, and suitable deflectors within said stack, substantially as described.

3. In a steam-carriage in combination with the mud-guards, two horizontal longitudinally-extended stacks outside of said body and open at both ends, each one having one of its ends extending through its corresponding mud-guard, a draft-tube in connection with each one of said stacks, and deflectors pivoted within said stacks upon the side thereof, adjacent to the draft-tube, substantially as described.

4. In a steam-carriage in combination with the mud-guards, a longitudinally-extended open-ended stack on each side of the carriage adjacent to and below the seat, and having their rear ends extended through their corresponding mud-guards and also having their forward ends flush with the front of the forward seat, a draft-tube connected with each of said stacks and suitable deflectors pivoted within said stacks to prevent the wind from blowing down said draft-tube, substantially as described.

In testimony whereof I hereunto affix my signature in the presence of two witnesses.

ROLLIN H. WHITE.
